UNITED STATES PATENT OFFICE.

HERMAN C. MAISE, OF DETROIT, MICHIGAN, ASSIGNOR TO BRIGGS MANUFACTURING COMPANY, OF DETROIT, MICHIGAN, A CORPORATION OF MICHIGAN.

COWL VENTILATOR.

Application filed October 29, 1923. Serial No. 671,608.

This invention relates to ventilators and refers more particularly to cowl ventilators for vehicle bodies.

- An object of the invention is to provide 5 a strong and durable ventilator that is simple in construction and that may be easily and quickly adjusted for controlling the passage of air through the cowl of a vehicle body.
- 10 Another object is to provide simple and efficient means for automatically retaining the ventilator cover in any adjusted position.

With the above and other objects in view 15 the invention consists in certain novel features of construction as will be more fully described and particularly pointed out in the appended claims.

In the accompanying drawings:—

Figure 1 is a top plan view of a portion 20 of a vehicle and showing a cowl ventilator embodying my invention applied thereto;

Figure 2 is a sectional view taken on line 2—2 of Figure 3;

Figure 3 is an enlarged central longitudinal vertical sectional view through the 25 cowl with parts in elevation.

Referring now to the drawings in which like characters of reference designate corresponding parts throughout the several views, 30 the numeral 1 designates a cowl of a vehicle body having an air inlet opening 2 and an upstanding transversely curved flange 3. This flange preferably extends around the edges of the opening and prevents moisture flowing downwardly along the cowl from 35 entering the vehicle body through the ventilating opening.

For controlling the passage of air through the opening 2, I preferably provide a cover 40 4 having a depending marginal flange 5 that is adapted to surround the flange 3 on the cowl when the cover is in closed position. For deflecting air downwardly through the opening 2, I preferably provide a shield 6 45 that extends downwardly through the opening and that has a transversely extending flange 7 at its upper edge secured preferably by welding to the lower face of the cover 4. The shield 6 is also provided with 50 parallel wings 8 that extend forwardly from

the side edges thereof adjacent to the flange 7. Secured, preferably by welding, to the rear face of the shield 6, is a hinge bracket 9 having parallel rearwardly projecting flanges 10 that are preferably pivotally 55 mounted upon a pin 11 extending through parallel flanges 12 projecting downwardly from the ends of a hinge bracket 13 that is rigidly secured, preferably by welding, to the lower face of the cowl 1 adjacent to the 60 rear edge of the opening 2. Thus, the pivot 11 for the cover 4 is located below the cowl and is concealed thereby.

For moving the cover 4 to various positions of rotative adjustment, I preferably 65 provide a handle 14 having a flat extension 15 that is secured preferably by riveting to the rear face of the shield 6. The handle 15 preferably extends downwardly and rearwardly from the shield so that the grip 16 70 will be in a convenient position to be manipulated.

For automatically retaining the cover 4 in various positions of adjustment, I preferably 75 provide a bar or quadrant 17 that extends between a metal dash board 18 and an instrument board 19 of the vehicle body and that is provided adjacent to the rear end thereof with a centrally disposed longitudinally extending slot 20 through which 80 the handle 14 extends. The bar 17 is preferably bolted at one end to a transversely extending flange 21 at the lower edge of the instrument board and is provided at the other end with an upstanding flange 22 that 85 is preferably riveted to the dash board 18. Sleeved upon the handle 14 is a cup-shaped member 23 that is adapted to slide along the upper surface of the bar 17 and that is preferably pressed thereagainst by means of 90 a coil spring 24 that surrounds the handle. The upper end of the spring 24 is preferably secured to a transversely extending reinforcing flange 25 at the lower edge of the shield 6, while the lower end of the spring 24 preferably rests within the cup-shaped member 23. A tubular member 26 surrounds the handle 14 within the coils of the spring 24 and is preferably formed of resilient material to prevent the spring from rattling. 95 100

The bar 17 preferably inclines gradually downwardly from the dash board 18 to a point slightly beyond the forward end of the slot 20 and is preferably offset downwardly as shown at 27 adjacent to the instrument board 19. The slotted portion of the bar is preferably bent to provide a plurality of detents or corrugations 28 for receiving the cup-shaped member 23 to hold the handle 14 in various positions of adjustment.

In use, the handle 14 may be readily moved forwardly or rearwardly to raise and lower the cover 4. When the handle is positioned at the rear end of the slot 20 as shown by full lines in Figure 3 the pressure exerted by the spring 24 against the cup-shaped member 23 is in advance of the handle so that the cover 4 will be retained in closed position, whereas, when the handle 14 is moved to the position shown by dotted lines in Figure 3 the pressure exerted by the spring against the cup-shaped member is in rear of the handle, consequently, the cover 4 will be retained in raised position.

While it is believed that from the foregoing description the nature and advantages of the invention will be readily apparent, I desire to have it understood that I do not limit myself to what is herein shown and described and that such changes may be resorted to when desired as fall within the scope of what is claimed.

What I claim as my invention is:

1. In a vehicle body, the combination with an instrument board, a dash board, and a cowl extending between said boards having an air inlet opening, of a forwardly opening closure for the opening having a part pivotally mounted beneath the cowl, an operating handle rigidly secured to said part so as to be concealed thereby when the closure is moved to open position, a bar extending between the instrument board and dash board in spaced relation to said closure and cowl having a longitudinally extending slot receiving the handle, and means sleeved upon said handle between the bar and closure engageable with the bar for holding the handle and closure in adjusted position.

2. In a vehicle body, the combination with an instrument board, a dash board, and a cowl extending between said boards having an air inlet opening, of a closure for the opening pivotally connected to the cowl, an operating handle secured to the closure to swing therewith, a bar extending between the instrument board and dash board having a longitudinally extending slot receiving the handle, an element sleeved on the handle between the bar and closure engageable with the bar for holding the handle and closure in adjusted position, a spring sleeved upon the handle and pressing the element against the bar, and a tube surrounding the handle

within the spring to prevent the latter from rattling.

3. In a vehicle body, the combination with an instrument board, a dash board, and a cowl extending between said boards having an air inlet opening, of a bracket secured to the under side of said cowl, a closure for the opening having a depending deflector at one end pivotally connected to said bracket, an operating handle secured to the deflector below the bracket so as to be concealed when the closure is opened, a bar terminally secured to the instrument board and dash board below the deflector having a longitudinally extending slot receiving the handle, and yieldable means carried by the handle between the bar and closure engageable with the bar for holding the handle and closure in adjusted position.

4. The combination with a cowl having an opening therein, of a cover for said opening, a depending shield secured to the lower face of the cover for deflecting forwardly and downwardly air admitted through said opening, means for adjusting said cover including a handle having a shank rigidly secured to said shield, and means for yieldably holding said cover in adjusted position including a bar extending longitudinally of the cowl beneath the shield, and means carried by the handle between the bar and the shield yieldably engageable with the bar.

5. The combination with a cowl having an opening therein, of a cover for said opening, a depending shield secured to the lower face of said cover for deflecting downwardly air admitted through said opening, a reinforcing flange on the said shield, a handle for adjusting said cover having a shank secured to said shield, a bar extending longitudinally of the cowl below said shield having spaced recesses therein, and a part carried by said handle shank engageable with said recesses and said reinforcing flange for retaining said cover in adjusted position.

6. The combination with a cowl having an opening therein, of a cover for said opening, a depending shield secured to the lower face of said cover for deflecting forwardly and downwardly air admitted through said opening, a projection on said shield, a handle having a shank rigidly secured to said shield for adjusting said cover, and means for maintaining said cover in adjusted position including a bar extending longitudinally of said cowl beneath said shield having spaced projections, a part carried by the handle engageable with said projections, and yieldable means abutting said projection on the shield for maintaining said part in engagement with said bar.

7. The combination with a cowl having an opening therein, of a cover for said opening, a depending shield secured to the lower face of the cover for deflecting forwardly

and downwardly air admitted through said opening, means for adjusting said cover including a handle having a shank rigidly secured to said shield, and means for yieldably holding said cover in adjusted position including a bar extending longitudinally of the cowl beneath the shield, and means sleeved upon said handle between the bar

and the shield adapted to yieldably engage the bar in advance of the handle when the cover is closed and in the rear of the handle when the cover is open. 10

In testimony whereof I affix my signature.

HERMAN C. MAISE.
